Design No 642

James L. Jackson, New York, N.Y.
 Letters Patent No 4425 Dated Feb 4, 1852

The Schedule referred to in this Letters Patent, and making part of the same.

To all whom it may concern:

Be it known, that I, James L. Jackson, of the City, County, and State of New York, have invented or produced a certain new and original design for a Grate Frame, and I do hereby declare the following, to be a full, clear and exact description of the same, reference being had to the accompanying drawing, representing one half of the frame finished, the other half, which is the same in configuration, in outline, and showing by sections the projection of the mouldings, ornaments &c.

The general outline of the frame is square, the jambs a. rise perpendicularly, and are surmounted by a semicircular top. In the inner margin, of the opening in the frame, which may be fitted with a summer piece, is finished with a plain lead moulding b, from which starts and extends outward a cavois moulding, terminating in a raised projection c, upon which is placed a cable c, extending around the frame, and supported on the bases f. of the jambs. In the upper corners are sunken panels g, finished off with a delicate lead and moulding, and in said panels are arranged arabesque flowers, leaves and stems, in alto relivo, having a rose in the centre, out of which branch two vines h, upon which are leaves, buds and full blown flowers, and which vines terminate near the two, extreme corners of the panel, conforming in their general direction, to the circular form of the cable c. Stems also project from the rose in the centre towards the extreme corners of the frame, upon which are buds

and leaves entwining each other.

The projector of the mouldings, cable &c. are seen in the sections A. B. on the right of the drawing.

Having thus described the nature of my design, what I claim therein as new, and desire to secure by Letters Patent is the combination and arrangement of ornamental figures herein represented, and forming an ornamental design for a Grate frame.
